UNITED STATES PATENT OFFICE.

JEREMIAH JOHNSON, OF PORT COLBORNE, ONTARIO, CANADA.

AUTOMATIC TRAIN CONTROL.

1,304,778.

Specification of Letters Patent.

Patented May 27, 1919.

Application filed July 22, 1918. Serial No. 246,125.

To all whom it may concern:

Be it known that I, JEREMIAH JOHNSON, of the town of Port Colborne, in the county of Welland, in the Province of Ontario, 5 Canada, have invented certain new and useful Improvements in Automatic Train Controls, of which the following is the specification.

My invention relates to improvements in 10 automatic train controls and the object of the invention is to devise means for automatically stopping a train before reaching a track opening such as is formed by an open switch or by an open swing bridge 15 and it consists essentially of the following arrangement and construction of parts as hereinafter more particularly explained.

Figure 1, is a plan view showing a portion 20 of a railway track and my device applied thereto.

Fig. 2, is a perspective detail of the circuit opening switch used in connection with my device.

In the drawings like characters of reference 25 indicate corresponding parts in the various figures.

1 indicates the main line formed by the rails 1^x and 1'. 2 and 3 indicate switch points leading to a siding and operated in 30 the usual manner by a connecting switch bar 4 extending beneath the rails 1^x and 1' of the main line, which bar is connected in the usual manner to the switch stand 5 which is provided with the usual operating lever 5^x. 35 The switch points in the drawing are shown in the closed position.

6 indicates a pivoted arm of suitable conducting material mounted upon one of the ties 1² of the railway line. The arm 6 passes 40 through an eye 4^x carried by the bar 4. 7 indicates a contact strip which bridges a recess formed in the side of the tie 1³, the intermediate portion of the contact strip 7 being curved downward at 7^x to form a de- 45 pending loop. When the switch is in the closed position as shown in the drawing the free end of the pivoted arm 6 rests in contact with and upon the horizontal portion of the contact strip 7. 8 and 9 indicate con- 50 tact pieces preferably carried by the ties 1⁴ and 1⁵ of the railway track, the contact piece 9 being connected by a wire 10 to the contact strip 7, and the contact piece 8 by a wire 11 to the pivoted arm 6.

55 12 indicates the body of an engine beneath which is carried a pair of contact

strips 13 and 14 in alinement with the contact pieces 8 and 9. 15 indicates the shaft which operates the pneumatic brake mechanism of the train. 15^x indicates a crown 60 wheel carried by the shaft 15. 16 indicates a motor also carried by the engine and provided with a pinion 16^x mounted upon its shaft in engagement with the crown wheel 15^x. 17 indicates a battery, one terminal of 65 which is connected by a wire 18 to one terminal of the motor 16 and the other terminal by a wire 19 to the contact strip 13. The contact strip 14 is connected by a wire 20 to the other terminal of the motor. Interposed in the wire 20 is a manually operated switch 20^x by which the circuit may be manually opened if desired.

When a train is passing over the switch points 2 and 3 of the siding the switch will, 75 of course, be in the closed position and when in this position the arm 6 is in contact with the strip 7 as above described. If another train should approach the switch before the switch is again opened the contact strips 80 13 and 14 carried by the engine when contacting with the strips 8 and 9 will close a circuit which passes from one terminal of the battery through the wire 19 to the strip 13, from thence to the strip 8 by wire 11 to 85 the arm 6 in contact with the strip 7 and from the strip 7 by the wire 10 to the contact piece 9 to the contact strip 14 connected by the wire 20 to one terminal of the motor 16, then through the motor to the wire 18 90 leading to the other terminal of the battery. By this means the motor will be operated and the brake mechanism set to stop the train.

When the switch is thrown to the open 95 position so that the main line would be open the arm 6 is automatically carried by the opening of the switch over the recess portion 7^x of the strip 7 thereby breaking the contact and, therefore, breaking the circuit 100 above described for operating the brake mechanism of the train, allowing the train upon the main line to pass through and pass the switch without interruption.

When it is desired to pass a train on to 105 the siding the circuit may be opened manually by the switch 20^x on the engine when the engineer knows that the switch is closed, and that it is free for him to pass on to the siding.

110 Although I have shown a switch as the means whereby the track may be opened and

closed it will, of course, be understood that track openings may be formed by various other means, such as by a swing bridge which, when in the open position, will leave 5 the track open, and it will be necessary by similar means to automatically stop the train when an opening is formed in the main line. Also if desired the circuit might be extended to a tower located along the track in which is 10 located a switch whereby the switch operator in the tower can open and close the circuit in order to render the device operative or inoperative as desired.

From this description it will be seen that 15 I have devised a very simple device whereby trains may be automatically stopped when an opening is formed in the main line either by an open switch or by an open swing bridge or by any other means so as to prevent 20 collisions between a train passing on to the siding and a train which is intended to pass directly along the main line and also means which will prevent wrecks caused by leaving open a swing bridge and also prevent 25 wrecks occurring by leaving a switch closed at the time when the passage of a fast train over the main line is due.

What I claim as my invention is:

1. The combination with a railway track 30 adapted to be opened and closed, a pair of contacts located between the rails, a stationary contact located adjacent to the switch, a circuit wire connecting the stationary contact with one of the contacts between the rails, a circuit wire connecting a movable contact with the other contact between the rails, means for carrying the movable contact into engagement with the stationary contact by the closing of the switch 35 and out of contact by the opening of the switch, an air brake mechanism, an operating motor therefor, and means carried by the engine co-acting with the contact strips between the rails for closing the circuit 40 through the motor, and means for energizing the circuit.

2. The combination with a railway track 45 adapted to be opened and closed, a pair of contacts located between the rails, a stationary contact located adjacent to the switch, a circuit wire connecting the stationary contact with one of the contacts between the rails, a circuit wire connecting the mov-

able contact with the other contact between the rails, means for carrying the movable 55 contact into engagement with the stationary contact by the closing of the switch and out of contact by the opening of the switch, an air brake mechanism, an operating motor therefor, a pair of contact strips carried by 60 the engine adapted to contact with the contact strips between the rails, a circuit wire connecting one contact strip with one terminal of the motor, a circuit wire connecting the other contact strip with the other terminal of the motor, and means for energizing 65 the circuit.

3. The combination with a railway track adapted to be opened and closed, a pair of contacts located between the rails, a stationary contact located adjacent to the switch, a circuit wire connecting the stationary contact with one of the contacts between the rails, a circuit wire connecting a movable contact with the other contact between the rails, means for carrying the movable contact into engagement with the stationary contact by the closing of the switch and out of contact by the opening of the switch, an air brake mechanism, an operating motor therefor, means carried by the engine co-acting with the contact strips between the rails for closing the circuit through the motor, means for energizing the circuit, and manual means located in the engine for breaking a circuit leading to the motor.

4. The combination with a pair of contact plates adapted to be located between the rails of a track, circuit wires leading from 90 each contact plate and a circuit opening switch located in one of the wires, of a pair of contact strips carried by the engine adapted to contact with the contact strips between the rails, a circuit wire extending 95 from one of the contact strips, a circuit wire extending from the other contact strip, a motor, to the terminals of which the aforesaid wires are connected, an air brake shaft, means operated by the rotation of the motor 100 for operating the air brake shaft, and means for energizing the circuit.

JEREMIAH JOHNSON.
